UNITED STATES PATENT OFFICE

JOSEPH A. MCKERCHER, OF NEW WESTMINSTER, BRITISH COLUMBIA, CANADA

PAINT SURFACING AND DISTRIBUTING MACHINE FOR DIPPED SHINGLES

Application filed August 9, 1927. Serial No. 211,776.

This invention relates to a machine for distributing and improving the painted or stained surfaces of shingles immediately after dipping.

5 Its object is to provide means whereby the surplus paint or stain on a dipped shingle may be quickly removed so that the shingles may be immediately bundled for shipment without the probability of their becoming 10 cemented together and consequently injuring the painted surface or the shingle itself.

A further object gained by the device is that the texture of the painted surface is evenly maintained and that the dipping medium is forced into the crevices of the shingle which leaves the machine in a practically dry 15 condition.

With these and other objects in view I arrange my machine to consist of two horizontal 20 rolls which revolve slowly in bearings carried by the vertical members of a simple framework, on the top of which is mounted a motor which drives the aforesaid rolls by worm gear from a chain sprocket wheel over- 25 hanging the end of the machine.

The horizontal rolls are covered with carpet or other like textile fabric and a double row of brushes extends between the side or end frames in front and in a line with the 30 adjacent horizontal peripheries of the carpeted rolls.

The brushes may be arranged in sections convenient for removal and are placed with their bristles opposite so that the shingles 35 may be introduced between them and thence follow on between the two rolls by which they are drawn forward through the machine to be deposited upon a receptacle bench for disposal.

40 Sprocket wheels are provided at the end of each of the rolls which are revolved conveniently by a chain drive, the lower roll receiving the motion direct from a sprocket wheel on the worm shaft spindle driven by the 45 motor.

Contrary motion is given to the upper carpeted roll by a second sprocket wheel on the lower roll which drives diagonally to the opposite side of the roll sprocket and thence 50 follows around an adjustable and a fixed

sprocket to obtain the required driving condition.

One or other set of the brushes may receive a slight oscillating or endwise motion if desired for the purpose of improving the texture of the painted surface. 55

The invention is more clearly exhibited by the drawings herewith forming part of this invention and in which Fig. 1 is a side elevation and Fig. 2, an end elevation; and in which the driving motor is indicated by 3, the worm wheel spindle 4 carrying the main driving sprocket wheel 5, this driving gear being carried by the top member 6 of the supporting framework, the side or end frames 7 of which support the bearings for the spindles 8 of the horizontal rolls 9. These latter are covered with carpet over the whole of their circular surfaces and are driven in opposite 60 directions by a chain. 65

A double row of brushes 10 extends between the two end frames 7 being placed with their bristles opposite so that the shingles may be inserted between them. The spindle of the lower carpeted roll carries on its extremity two chain sprocket wheels 11 and 12. The former is in engagement with the motor driven sprocket wheel 5 by the driving chain 13 and the latter rotates the upper cylindrical roll 9 by its sprocket wheel 14 by the driving chain 15 which is kept in suitable tension by the fixed idler 16 and the adjustable idler 17, the latter being supported by the lever 18 under the influence of the spring 19. 70 75

When desired for improving the character of the painting work one of the rows of brushes 10 may be made to give a slight oscillating motion by connection to the cam lever 20 acting in conjunction with the revolving side cam 21 and against the action of the spring 22 which gives the return motion to the brush carrier. 80 85

An operating bench across the front of the framework is shown at 23 and a receptacle bench upon which the finished shingles are delivered is shown at 24. 90 95

The process of operation in connection with this machine is to first dip the shingles in a paint or stain bath from which they are lifted to the operating bench 23 and fed by 100

manual labour between the horizontally disposed brushes 10 receiving thereby an even distribution to their coat of paint.

The shingles are thence pushed forward to be received by the carpet covered rolls being thereby drawn through between them and delivered upon the bench 24 ready for the bundling operation without further delay or the necessity for other drying operations.

Having now particularly described my invention what I claim and desire to be protected in Letters Patent, is:

In a machine of the type described the combination comprising, a framework, a pair of superposed horizontal rolls carried by said framework, said rolls having their circular peripheries covered with a carpet-like fabric and being revolved in opposite directions, two rows of rigidly and oppositely held brushes, said two rows being in the same vertical plane and having their horizontal plane of contact in horizontal alignment with the line formed by the adjacent cylindrical surfaces of said rolls whereby shingles may be hand fed between said rows of brushes to be received therefrom by the adjacent said pair of rolls, a motor carried by said framework and adapted to operate said machine through worm gear and cross shaft, a sprocket wheel on extremity of the spindle of the lower said roll, a corresponding sprocket wheel on said cross shaft, a chain engaging said sprocket wheels, a second sprocket wheel on said lower roll spindle, a sprocket wheel on the spindle of said upper roll, a fixed idler chain wheel, an adjustable idler chain wheel, a chain engaging the last said four wheels and adapted to revolve the upper roll in a direction opposite to that of the lower roll, a cam revolvable on the axis of and with said adjustable chain wheel, a cam lever oscillating and pivotal on a bracket carried by said framework, a connecting means whereby the oscillation of said lever is utilized to oscillate one row of said brushes against the action of a spring, all substantially as described and shown.

In testimony whereof I affix my signature.
JOSEPH A. MCKERCHER.
